[57] **ABSTRACT**

A test method is provided for determining whether a person is a schizophrenic, which comprises suitably treating a plurality of test animals, obtaining a sample of the person's blood, pre-mixing the blood, or preferably the plasma therefrom with 3,4-dimethoxyphenylethylamine, internally administering the mixture to the test animals, and maintaining the animals under aggregated or crowded conditions while observing their behavior for amphetamine-like reaction and lethality as an indication of the presence of schizophrenia in the blood sample donor.

5 Claims, No Drawings

DIAGNOSTIC TEST FOR SCHIZOPHRENIA

BACKGROUND OF THE INVENTION

Prior art methods for diagnosing schizophrenia are generally psychological in nature, and therefore highly subjective. It would consequently be highly desirable to have a positive chemical or clinical test for schizophrenia which would be more objective, more precise, and more highly reproducible.

It has been previously demonstrated that there is a urinary excretion of 3,4-dimethoxyphenylethylamine (DMPEA) by schizophrenic patients which is not present in analyses run analogously on urine from non-schizophrenic subjects. Additionally, the presence of abnormal protein factors have been shown to be present in the blood plasma of schizophrenic patients. However, the analyses for the presence of these components per se are not sufficiently developed to provide a diagnostic test for schizophrenia.

SUMMARY OF THE INVENTION

It is an object of the present invention to provide a diagnostic clinical test for the existence of schizophrenia in a person. It is a further object to provide a test of the type described which is sensitive, precise, accurate, and reproducible. It is a further object to provide a diagnostic test which can be carried out in a relatively short time and which is relatively inexpensive. Additional objects and advantages of the invention will be apparent to one skilled in the art, and still other advantages will become apparent hereinafter.

DESCRIPTION OF THE PREFERRED EMBODIMENTS

According to the invention, a plurality of test animals are first pretreated with a monoamine oxidase inhibitor (MAO), as for example, phenylisobutylhydrazine. A sample of blood is taken from the patient and mixed with DMPEA, and after incubation, the mixture is injected into a plurality of the test mice, and the mice maintained in the aggregated or crowded state where they are observed for a period of about 4 hours for exhibition of amphetamine-like reaction and lethality. It has been found that when the blood from a schizophrenic person is utilized either as serum or preferably as plasma, a high degree of positive amphetamine-like reaction and a high degree of lethality of the test animals will be observed.

Reports containing detailed information with regard to the method of the present invention are contained in a report entitled *Schizophrenic Plasma induction of an Action of DMPEA* by Charles D. Proctor et al. in *The Pharmacologist* (Vol. 9, No. 2, p. 238,) Fall Issue (1967), and also two reports in *Archives Internationales de Pharmacodynamie et de Therapie*, Vol. 172, No. 1, March, 1968, Brussels Belgium, one entitled "AN INFLUENCE OF BLOOD PLASMA FROM SCHIZOPHRENICS ON AN ACTION OF 3,4-DIMETHOXYPHENYLETHYLAMINE," pp. 95-105, and the other entitled "FACTORS AFFECTING AN INFLUENCE OF BLOOD PLASMA FROM SCHIZOPHRENICS ON AN ACTION OF 3,4-DIMETHOXYPHENYLETHYLAMINE," pp. 106-121, the entire contents of which reports are hereby incorporated herein by reference.

The following examples are given by way of illustration only and are not to be construed as limiting.

Example 1: Test procedure.

Five to ten Webster mice (20-30 gm) are injected intraperitoneally with 30 mg/kg JB-835 (phenylisobutylhydrazine) in either the hydrochloride or sulfate, or any other suitable form 3 hours prior to further test injections. Intraperitoneal injection here and elsewhere in the test is at volume level of 0.01 ml/gm. wt. of mouse, e.g., JB-835 concentration in the injection solution is 3 mg/cc in distilled water.

Two and one-half hours later 0.2 ml. of the plasma from the patient being tested is added to 1.8 ml. of a solution of 5.56 mg/ml DMPEA (3,4-dimethoxyphenylethylamine in free base form) in distilled water in a small test tube. Solution volume measurements are made with a 1 ml. tuberculin syringe. The

7 tube is tightly capped at once. The plasma DMPEA solution is placed in an incubator set at 37° C immediately and incubated immediately at 37° C for 30 minutes. 0.01 ml/gram (mouse wt.) of the incubated DMPEA-plasma solution is injected intraperitoneally into the JB-835 pretreated mice. The mice are aggregated at once by placing them five per compartment in the compartment(s) of a No. 101 Keystone plastic mouse cage divided by means of a four-compartment, Keystone stainless steel cage divider. Cage top (Keystone model no. 101-std.) must be on the cage and should be weighted down with a ringstand bottom. One-half inch depth of sawdust is present in bottom of the compartmentalized cage. In vitro part of test must be carried out at room temperature of 70°-74° F. The mice are observed for 4 hours, observing for amphetamine-like reaction and lethality. Evaluation of quality of the "amphetamine-like" reaction in the test is performed as described in Chance, M.R.A., *J. Pharmacol. Exptl. Therap.* 87:214 (1946).

20 Guidelines used in establishing the quality rating for the "amphetamine-like" reactions in the test are as follows:

Very slight positive reaction: salivation with increase in locomotor activity but with none of the mice assuming "defensive" postures (mainly rearing up on their hind legs as described by Chance, ref. vide supra);

25 Slight positive reaction: characterized by salivation with definite increase in locomotor activity but no assumption of defensive postures;

Moderate positive reaction: animals show salivation, increased locomotor activity, and assumption of defensive postures in some but not all of the animals;

Positive reaction: animals show salivation, marked increase in locomotor activity and development of defensive posture in all of the animals.

30 Example 2: Clinical tests.

Using the method of Example 1, plasma was taken from the blood of 12 acute, typical schizophrenics, six acute rapidly remitting schizophrenics, and 10 non-schizophrenics. Additionally, six trial tests were made substituting 0.9% aqueous NaCl solution for plasma. Right after plasma-DMPEA injection the mice were aggregated (Arch. into Pharmacodyn., 163: 79, 1966) and observed for amphetamine-like reaction (ALR) and 4 hour lethality (L). Results showed: with 12 acute, typical schizophrenics, marked + ALR, 80-100% L; with six acute rapidly remitting schizophrenics, moderate + ALR, 20-40% L; with 10 non-schizophrenics, - ALR, 0% L; six trials substituting 0.9% NaCl for plasma, - ALR, 0% L.

40 45 Table I below illustrates the effect of removing any one of the three important components necessary to give a positive test according to the invention.

TABLE I

Influence of Deletion of Components on the Effect of the 30 mg/kg JB-835 — 50 mg/kg DMPEA — Schizophrenic Plasma System in Aggregated Mice.

Example	Drug and Drug Dosage ¹⁾	DMPEA	Amphetamine-Like Reaction with:	% Lethality (n = 10)
3	30 mg/kg JB-835 50 mg/kg DMPEA	physiol. salin	(-)	0%
4	30 mg/kg JB-835	- physiol.	(-)	0%
5	50 mg/kg DMPEA	saline	(-)	0%
6	50 mg/kg DMPEA	schizo- phrenic plasma	(-)	0%
7	30 mg/kg JB-835 50 mg/kg DMPEA	schizo- phrenic plasma	(+)	100%

¹) JB-835 was given intraperitoneally (i.p.) 3 hours prior to DMPEA injection. DMPEA was given i.p. immediately prior to aggregation of the mice. When either JB-835 or DMPEA was omitted, physiological saline was administered as a substitute, "sham" injection at analogous volume and time schedule.

²) Plasma used in both Examples 6 and 7 was from the same blood sample withdrawn from an unmedicated, acute typical schizophrenic patient. Plasma was added to 5.56 mg./ml. DMPEA at 1:9 volume, incubated at 37° C. for 30 minutes right before i.p. injection followed by immediate aggregation of animals. Physiological saline was substituted for plasma where indicated.

Statistical Analysis: *p* value, X_c^2 : Example 7 vs. any other group: $p < 0.0005$.

The findings which have been presented in Table I appear to support the essentiality of having the intact combination of MAO inhibitor, DMPEA and plasma from a schizophrenic patient in the biological test system under study in order to produce an amphetamine-like reaction and lethality. Consideration of the results reveals that neither of these responses were yielded under the following conditions of deletion from the three component system in question: absence of the schizophrenic plasma (Example 3); 30 mg/kg JB-835 pretreatment of animals present but the other two components absent (Example 4); 50 mg/kg DMPEA given along (Example 5); 50 mg/kg DMPEA incubated with schizophrenic plasma and given to mice not pretreated with JB-835 (Example 6). The lack of response in all of these situations is in marked contrast to the definite responses obtained with the intact three component system of JB-835 premedication-incubated DMPEA-schizophrenic plasma injection (Example 7). In another experiment (carried out using a schizophrenic plasma different from the one used to supply data in Table I) it was revealed that incubating the plasma with physiological saline (in lieu of DMPEA solution), and injecting this into 30 mg/kg JB-835 pretreated, aggregated mice did not produce the responses. This was in spite of the fact that running the test on this plasma with its use making the three components intact in the system produced positive amphetamine-like reaction and 80 percent lethality (X_c^2 : $p < 0.002$).

Table II below illustrates the effects of aggregation or crowding of the test animals as opposed to solitary conditions.

TABLE II

Effect of Uncrowding: 30 mg/kg JB-835 ⁽¹⁾ — 50 mg/kg DMPEA — Typical Acute Schizophrenic Blood Plasma ⁽²⁾ System in Aggregated and Unaggregated Mice.

Example	Degree of Aggregation	Amphetamine-Like Reaction (+) or (-)	% Lethality (n = 10)	<i>p</i> value X_c^2
8	Crowded	(+)	100%	$p < 0.0005$
9	Uncrowded, Solitary	(-)	0%	

⁽¹⁾ JB-835 given i.p. 3 hours prior to DMPEA injection.

⁽²⁾ Plasma used in both tests was from the same blood sample withdrawn from an unmedicated typical acute schizophrenic patient. Plasma was added to 5.56 mg./ml. DMPEA at 1:9 volume, and incubated at 37° C. for 30 minutes immediately before i.p. injection followed by immediate aggregation of animals.

Although phenylisobutylhydrazine is the preferred monoamine oxidase others may be used, as for example, iproniazid, 1-isonicotinyl-2-isopropylhydrazine; phenylisopropylhydrazine; and 1-phenylisopropyl-2-isopropylhydrazine. It is only necessary that the agent have the capability of producing MAO inhibition *in vivo*.

In the present tests described intraperitoneal injection was used for administration to the mice. However, other methods may be used, as for example, intramuscular, subcutaneous, and intravenous.

Mice have been used as the present standard test animal, since they are inexpensive and easy to handle. However, other standard test animals such as rats, rabbits, guinea pigs, etc., may be used.

The DMPEA must be used in the free base form in order that the present test be effective. Weak acid salts, i.e., acetates may also be used.

Table III below illustrates the effect of floor space within which the mice are aggregated with respect to test results.

TABLE III

Effect of Variation in Available Floor Space/Mouse on the JB-835 — Schizophrenic Plasma*—DMPEA Test Run on Mice Aggregated in Groups of Five Mice Per Compartment.

Example	Floor Space/ Mouse, cm. ²	Amphetamine-Like Reaction (+) or (-)	% Lethality** (n = 10)
10	25 cm. ²	(+)	100%
11	50 cm. ²	(+)	80%
12	100 cm. ²	(+)	50%
13	400 cm. ²	slight (+)	10%

*The same schizophrenic plasma sample was used in all of the concurrent runs of the test shown.

**Example 10 or 11, each compared with Example 13: X_c^2 , $p < 0.05$, each instance.

Table IV below shows the results of experiments designed to determine the effect of time of injection of the MAO inhibitor.

TABLE IV

Effect of Time of Injection of 30 mg/kg JB-835 Prior to Incubated DMPEA — Schizophrenic Plasma Solution* on Test Response to JB-835—DMPEA-Plasma Test in Aggregated Mice.

Example	Hrs. 30 mg/kg JB-835 was injected i.p. Prior to DMPEA- Plasma Injection	Amphetamine- Like Response (+) or (-)	% 4 hr. Lethality (n = 10)**
14	1 hr.	very slight (+)	10%
15	2 hr.	slight (+)	10%
16	3 hr.	(+)	80%
17	6 hr.	(+)	80%
18	12 hr.	(+)	70%
19	24 hr.	(+)	70%

*The same schizophrenic plasma was used in all tests shown.

**Either Example 14 or Example 15 compared separately with each of any of the other Examples. X_c^2 , $p < 0.05$.

Table V below illustrates the effect of varying the incubation period at 37° C in vitro of plasma solution and DMPEA.

TABLE V

Effect of Incubation Time at 37° C in Vitro for DMPEA-Schizophrenic Plasma Solution on JB-835-DMPEA-Plasma* Test Response in Aggregated Mice.

Example	Time, Min., of Incubation of DMPEA-Plasma Solution Before Injection	Amphetamine- Like Response (+) or (-)	% 4 hour Lethality (n = 10)**
20	none	(-)	0%
21	10 min.	very slight (+)	10%
22	15 min.	moderate (+)	20%
23	30 min.	(+)	100%
24	35 min.	(+)	100%

*The same schizophrenic plasma was used in all tests shown.

**Either Example 23 or 24 compared separately with each of any of the other Examples. X_c^2 , $p < 0.05$.

Table VI below shows results of varying the temperature of 30 minute incubation of plasma and DMPEA.

TABLE VI

Example	Temp. for Incubation of DMPEA-Plasma Solution	% Lethality (n = 10)
25	4°C.	0%
26	15°C.	0%
27	20°C.	10%
28	25°C.	40%
29	37°C.	100%
30	45°C.	40%
31	80°C.	0%

(boiling water bath)

Table VII below indicates the effect of varying the dosage of DMPEA.

TABLE VII

Example	Dose of DMPEA yielded from injection of DMPEA-Plasma Solution	Conc. of DMPEA (free base) in Solution added to Plasma at Vol. Ratio 9:1	% Lethality (n = 10)
32	20 mg./kg.	2.22 mg./ml.	0%
33	25 mg./kg.	2.78 mg./ml.	10%
34	30 mg./kg.	3.34 mg./kg.	10%
35	40 mg./kg.	4.44 mg./ml.	40%
36	50 mg./kg.	5.56 mg./ml.	100%
37	60 mg./kg.	6.67 mg./ml.	100%
38	70 mg./kg.	7.78 mg./ml.	100%

Amphetamine-like response occurred over the whole range of 20 mg/kg - 70 mg/kg DMPEA. Significant lethality useful for testing occurred over the range 40 mg/kg. - 70 mg/kg. 40 DMPEA.

According to the findings discussed above, three components are required for elicitation of the responses which have been observed. These requirements are: that the aggregated mice used be pretreated with an MAO (monoamine oxidase) inhibitor, as for example, JB-835; that DMPEA be present in the system; and that suitable means be afforded for the DMPEA to interact with some factor or factors present in the blood of schizophrenic patients but not present in blood taken from non-schizophrenics. Aside from the inference of CNS (central nervous system) action derived from the requisite inclusion of the MAO inhibitor in the system, the requisite nature of all of these three components to elicitation of response in the biological system presents other implications. The critical requirement for interaction between DMPEA and some schizophrenic plasma factor (or factors), considered together with the probable CNS nature of the test response, is not incompatible with the hypothesis that the interaction arranges for increased transport of DMPEA across the blood-brain barrier to effect response. An alternative possibility, likewise neither proved nor disproved by the present 45

data, is that some agent or system present in schizophrenic plasma (but not in non-schizophrenic plasma) protects DMPEA from alteration to an inactive product either in the process of incubation or in vivo or both. The nature of the results establishing essentiality of the three critical components in the system in order to evoke response certainly tends to support rather than detract from the notion that at least a part of the process of schizophrenic reaction may be associated with an altered metabolism involving DMPEA and production of blood proteins which are specific (either by presence or by relative level) to the process of schizophrenic reaction.

Present results indicate that in consideration of the relative potential diagnostic utility of the test system for schizophrenic reaction, plasma from the subject will probably have greater utility than will serum. It was ascertained in comparative runs of the test, utilizing serum and plasma from the same patient, that qualitatively greater biological responses were obtained with plasma. However, either plasma or serum may be operationally used.

The present results also indicate that changing the social situation of mice subjected to this test system to uncrowded solitary confinement completely reversed the lethality which was obtained when similarly treated mice were aggregated.

It is to be understood that the invention is not to be limited to the exact details of operation or exact compounds shown and described, as obvious modifications and equivalents will be apparent to one skilled in the art, and the invention is therefore to be limited only by the scope of the appended claims.

I claim:

1. A method for diagnosing schizophrenia in a person comprising the following steps:

1. pretreating a plurality of test animals selected from the group consisting of mice, rats, rabbits and guinea pigs by internally injecting an amount of a monoamine oxidase inhibitor effective to inhibit monoamine oxidase in said test animals,
2. mixing a blood serum or plasma sample taken from the person with 40 mg/kg to 70mg/kg of 3,4-dimethoxyphenylethylamine based on the weight of said test animals and incubating the mixture so prepared for a period of about 30 minutes at a temperature of 25° to 45° C.,
3. internally injecting the mixture (2) into said test animals at least 3 hours after the injection of said MAO inhibitor, and
4. observing the animals for a suitable period of time while said animals are maintained in aggregated condition to determine whether they develop amphetamine-like reactions and lethality as indications of the existence of schizophrenia in the person from whom said blood sample was taken.

2. A method according to claim 1, wherein said monoamine oxidase inhibitor is phenylisobutylhydrazine.

3. A method according to claim 1, wherein said animals are mice.

4. A method according to claim 1, wherein said sample is plasma.

5. A method according to claim 1, wherein said sample is serum.
